CLAIM

The ornamental design for a cover for mobile phone, as shown and described.

DESCRIPTION

FIG. 1 is a perspective view of a cover for mobile phone showing our new design;

FIG. 2 is a front view of the cover for mobile phone of FIG. 1;

FIG. 3 is a rear view of the cover for mobile phone of FIG. 1;

FIG. 4 is a left side view of the cover for mobile phone of FIG. 1;

FIG. 5 is a right side view of the cover for mobile phone of FIG. 1;

FIG. 6 is a top plan view of the cover for mobile phone of FIG. 1; and,

FIG. 7 is a bottom plan view of the cover for mobile phone of FIG. 1.

The broken lines immediately adjacent the shaded areas represent the bounds of the claimed design while all other broken lines are directed to environment and are for illustrative purposes only; the broken lines form no part of the claimed design.

1 Claim, 5 Drawing Sheets
